UNITED STATES PATENT OFFICE.

ANDREW W. KNITTEL, OF EVANS CITY, PENNSYLVANIA, ASSIGNOR TO HIMSELF AND OSCAR W. SHOUP, OF SAME PLACE.

VALVE FOR OIL-WELL BAILERS.

SPECIFICATION forming part of Letters Patent No. 453,488, dated June 2, 1891.

Application filed February 26, 1891. Serial No. 382,880. (No model.)

To all whom it may concern:

Be it known that I, ANDREW W. KNITTEL, of Evans City, in the county of Butler and State of Pennsylvania, have invented a new and Improved Valve for Oil-Well Bailers, of which the following is a specification, reference being had to the annexed drawings forming a part thereof, in which—

Figure 1 is a longitudinal section of my improved valve, showing it closed. Fig. 2 is a longitudinal section taken on a plane at right angles to that of Fig. 1, showing the valve open; and Fig. 3 is a plan view of the valve.

Similar letters of reference indicate corresponding parts in all the views.

The object of my invention is to provide a valve for bailers used in oil-wells for removing salt-water and oil, which valve will be unaffected by the presence of sand.

My invention consists in the combination of an outer tube provided with a valve supported by a forked shank secured to the inner wall of the tube and projecting below the lower end thereof, and a sliding sleeve fitted to the tube provided with a valve-seat fitted to the valve and furnished with a forked, barbed rod or spear, which serves the double purpose of limiting the movement of the sleeve and of loosening the sand in the tube, all as hereinafter more fully described.

The tube A, forming the body of my improved valve, is designed to be attached to the bottom of the oil-well bailer. To the inner surface of the said tube A are secured the arms *a a* of the forked rod B, the lower end of which projects below the lower end of the tube A and receives the valve C.

The lower end of the tube A is provided with a fillet *b*, to which is fitted the upper end of the sleeve D. The lower part of the sleeve D is of the same diameter as the tube A, and at the middle of the sleeve, where the diameter is reduced, a valve-seat *c* is formed which

fits the valve C. Below the valve-seat the walls of the sleeve are slotted to allow of the free admission of oil or water, and above the valve-seat the sleeve is reduced in diameter for a short distance to allow it to pass freely through the fillet *b*.

To the inner surface of the upper end of the sleeve D are attached the arms *d d* of the forked rod E. The upwardly-projecting end of the said forked rod is provided with barbs *e e* for loosening the sand, which might otherwise pack in the tube A. The upward movement of the sleeve D is limited by the engagement of the shoulder *f* with the lower end of the tube A, and its downward movement is limited by the engagement of the forked rod E with the forked rod B.

When the bailer is lowered into the well, the lower end of the sleeve D strikes the bottom of the well and the tube A descends until it strikes the shoulder *f* of the sleeve. This operation opens the valve, when the water or oil enters the bailer. When the bailer is lifted, the sleeve drops and closes the valve.

Having thus described my invention, I claim as new and desire to secure by Letters Patent—

1. In a valve for oil-well bailers, the combination of the tube A, the forked rod B, valve C, the sleeve D, having the valve-seat *c* and the forked rod E, attached to the sleeve D and adapted to engage the forked rod B, substantially as described.

2. In a valve for oil-well bailers, the combination, with the tube A and sleeve D, of the rod E, attached to the sleeve and provided with barbs *e*, substantially as described.

ANDREW W. KNITTEL.
